copartnership

Application February 2, 1946, Serial No. 126,202

Term of patent 7 years

(Cl. D87—3)

To all whom it may concern:

Be it known that I, Benjamin Kalisher, a citizen of the United States and a resident of Poughkeepsie, county of Dutchess, and State of New York, have invented a new, original, and ornamental Design for a Handbag, of which the following is a specification, reference being had to the accompanying drawing, forming a part thereof, in which:

Fig. 1 is a front view of the handbag embodying the new design and showing the appearance of either the front or back of the handbag;

Fig. 2 is a side elevational view thereof;
Fig. 3 is a top plan view thereof; and

Fig. 4 is a fragmentary perspective view showing one of the plaques or rods of the design of the bag and the interlacing thereof at an end of the plaque or rod.

I claim:

The ornamental design for a handbag, substantially as shown.

BENJAMIN KALISHER.
